UNITED STATES PATENT OFFICE.

GEORGE HERBERT BROWN, OF BELFAST, IRELAND; KATHLEEN MARGARET BROWN, HERBERT BROWN, AND GEORGE BRAMATO BROWN EXECUTORS AND TRUSTEES OF SAID GEORGE HERBERT BROWN, DECEASED.

ELECTRIC SIGNALING ON RAILWAYS.

1,072,404.

Specification of Letters Patent.

Patented Sept. 2, 1913.

Application filed September 20, 1907. Serial No. 393,805.

To all whom it may concern:

Be it known that I, GEORGE HERBERT BROWN, a subject of the King of Great Britain, residing at 14 Dublin road, Belfast, 5 Ireland, have invented certain new and useful Improvements in Electric Signaling on Railways, of which the following is a specification.

This invention relates to an improved 10 electric block signaling system for railways. The system is so arranged that an incoming train automatically notifies or indicates its approach to the signal cabin controlling that section of the line on which it is and 15 also (if the line is clear) notifies or indicates its approach to the signal cabin controlling the next section of the line ahead and further gives a signal to the signal cabin controlling the section of the line just 20 left. Two rails or rods or the like are arranged parallel to one another in advance of each signal cabin and these rails or the like which are suitably insulated may be of any suitable length and are preferably laid 25 between the ordinary rails. These special rails, which I will hereinafter refer to as "signaling rails" or "ramp rails," are adapted to be charged with electricity from a source of electricity on the train, preferably 30 a dynamo on the engine, and by means of a contact brush or wheel which is normally pressed downward by one or more springs in the same manner as in Mackenzie's Patent No. 866,945, September 24th, 35 1907, and wires are led from the signaling rails of each section to the signal cabin of that section and indicating (red and green) lamps and bells are arranged in the circuits in any suitable and well known manner. 40 On each engine and also, preferably, in the guard's van of each train similar signaling bells, and (red and green) lamps are used and also if preferred a whistle in addition.

45 Each cabin is connected up with the signaling rails of the section ahead, and with the cabin behind, by means of properly insulated wires. The lever quadrants of the locking frame in each cabin, are provided 50 with insulated contact studs, the levers are also provided with corresponding studs, and the contacts are so arranged that when an engine is on the signaling area and the lever is in the position to indicate danger,

a circuit is closed whereby a danger lamp 55 is lighted in the signal cabin and also on the engine; and moreover should the lever be drawn forward in error to show "clear" while another engine is in the area ahead another circuit is closed which indicates 60 danger both in the cabin behind and on the engine in that area.

The first circuit just mentioned is supplied with electricity from the locally situated train, while the electricity for the second circuit is supplied from the train in the signaling area ahead.

With the present invention the advantage is obtained that should any defect or interruption in the signaling system arise 70 while the train is in motion such defect is at once made apparent to the driver in his cab by means of a suitable arrangement of electric lamps showing a green, red or white light respectively with the necessary mechanism for lighting same. The arrangement is such that, as long as the lamp showing the white light remains lighted, the driver knows that his signaling system is in proper working order, but, immediately such light 75 is extinguished and neither the red nor the green light referred to in the aforesaid specification, becomes visible, he knows that there is some defect or interruption and until such is remedied he must not proceed. 80

In order that my said invention may be properly understood I have hereunto appended explanatory drawings whereon:—

Figure 1 is a diagrammatic view of a section of a railway track showing two signal 90 cabins an engine being indicated on one of the signaling areas of these cabins. Fig. 2 is an end view of the cab of an engine showing diagrammatically the various connections between the cab signals and the trolleys. Fig. 3 is an enlarged detail of the switch lever *r* provided in each signal cabin.

Along a section of the track at each signal cabin conducting wires or rails *c* and *c'* are 100 laid which, as shown in Fig. 1, are placed beside the ordinary rails *l* and are supported at intervals in any suitable manner. An insulated wire *m* is led from the conducting wire *c* and by a branch wire *n* to the switch contact *o'* in the signal cabin 1, or 2 as the case may be, and a second insulated wire *p* is led from the signaling wire or rail *c'* by

branch wire n^1 to the switch contact o^2 . By means of the switch o when the lever r is pulled into position to indicate the line clear, independent contact can be made through the contacts o^1 and o^2 and a circuit completed as hereinafter described through the wires n and n^1 thereby connecting the green lamp 10 and the red or danger lamp 11, so that the signalman can communicate with the train officials by means of a series of flashing signals.

In each signal cabin there is, preferably, arranged a green lamp 10, a red lamp 11, and a white lamp 12, as shown in Fig. 1. Each lamp may have, in connection with it, a call bell suitably connected in circuit. From the wire m where it joins the wire n a wire m^1 is led to a branch wire w leading to the green lamp 10 and from the latter a wire t is led to the running rail l . From the wire t a branch wire t^1 leads to the white lamp 12 and from the latter a wire u leads to the wire q between the signal cabins. A branch wire v^1 also leads from the wire u to the contact stud v^5 . From the wire t a branch wire s^1 leads to the danger lamp 11 and from the latter a wire s leads to a wire p which leads to the contact rail c . A branch wire n^1 leads from the wire p to the switch contact stud o^2 and a branch wire v^2 leads from the wire p to the contact stud v^2 , and there is also led from the branch wire v^2 a branch wire v^4 which leads to the contact stud v^6 . A switch lever r is arranged as hereinafter explained to connect studs v^1 and v^2 and v^5 and v^6 .

As illustrated at Figs. 1 and 2, besides the distributing trolley x^1 for charging the contact rail cable or wire, there are two trolleys fitted underneath the engine or tender frame a preferably consisting of the usual grooved pulleys or wheels b and b^1 which normally contact with signaling rails, cables or trolley wires c and c^1 , (as shown in Fig. 1) being rotatably secured in the lower ends of vertical standards d movably fitted in brackets e suitably secured at their upper ends to the engine or tender frame a . Each of the brackets e is made with vertical slots 50 through which project horizontal pins d^1 fitted in the standards d the arrangement being such that the standards d and pins d^1 are capable of an up-and-down movement in the brackets e . x indicates a dynamo (or other source of electricity) on the engine. From the dynamo x the wire 7 passes to the distributing trolley x^1 while the wire 7^a connects the dynamo x to earth by way of the engine framing, and the wire 7^b from the dynamo x passes to the wire 7^c and so to the contact piece 7^d with which the contact pin d^1 contacts when the left hand trolley b (Fig. 2) is in the down position as shown in Fig. 2.

65 Fixed terminals f , f^1 are provided, one for

each trolley standard d and preferably consisting of the strip or plate of sheet metal suitably bent to shape and fitted to the frame a , these terminals f being arranged near the top of the standards e . A terminal f^1 fixed to the engine frame is also arranged in connection with the left hand trolley standard d and is connected by a wire g to the switch contact stud g^3 in the engine cab and from stud g^3 a wire g^4 is led through the white lamp 3 and bell to earth by way of the engine framing. This terminal f^1 has at its end an insulated contact 70 7^d which is connected with the source of electricity by wires 7^e and 7^b .

75 From the left hand terminal f a wire g^1 is led through the green lamp 1 and bell and to earth by way of the engine framing and from this wire g^1 a branch wire g^7 is led to the switch handle contact stud g^5 .

80 From the right hand terminal f a wire g^2 is led to the switch contact stud g^6 and from thence a wire is led through the red or danger lamp 2 and bell and whistle and to earth by way of the engine framing. At 85 the right hand side of engine a rest f^2 is provided for the pin d^1 of the trolley b^1 . This rest f^2 is not electrically connected. When the trolleys drop downward after the train leaves the signaling area the horizontal pin d^1 on the left hand standard d bridges the terminal f^1 and the insulated contact 7^d at the end of this terminal and through the wire g completes an electric circuit as hereinafter described to intimate to the driver 90 by means of a white light 3 in the cab of the engine that all is in order. When the train enters the next signaling area and the trolleys are properly in contact with the signaling rails, cables, or trolley wires c and c^1 the horizontal pins d^1 are raised or lifted 95 in the slots e^1 so that they come in contact with the terminals f , thereby giving an electrical connection through the wire g^1 with the green light G^r in the cab of the engine 100 and thereby indicating to the driver that he is in the signaling area.

105 To facilitate the up-and-down movement of the trolley standards d suitable springs may be fitted therein as indicated at d^2 .

110 The following is a description of the various circuits in the signaling system under this invention:—When the train is between the signaling areas the trolley b falls so that contact stud d^1 rests on terminal f^1 and contact 7^d and a circuit is thus completed between the dynamo x and the white lamp 3 in the engine cab in the following manner:—Current passes from the dynamo x by wire 7^b , 115 wire 7^c , contact piece 7^d , contact d^1 , terminal f^1 , wire g , contact g^3 , wire g^4 to white lamp 3 and then to the earth by the engine framing to which the dynamo is earthed. This circuit, when completed, shows the driver 120

that the apparatus is in working order and his dynamo α or other source of electricity supplying current.

When the train enters the signaling area of, say, cabin 1 and is traveling in a direction from left to right of the diagram Fig. 1 then the distributing trolley α^1 and the collecting trolleys b and b^1 are raised by and make contact with the signaling rails c and c^1 , the hereinbefore described circuit through the lamp 3 being thus broken by stud d^1 being lifted away from contact piece 7^1 and terminal f^1 and when the stud d^1 is so raised it makes contact with the upper terminal f and thereby another circuit is completed by current passing from the dynamo α by wire 7, (see Fig. 2) distributing trolley α^1 , ramp or signaling rail c , collecting trolley b , bracket d , contact stud d^1 , terminal f , wire g^1 , green lamp 1 in engine cab and to earth by engine framework. At the same time a third circuit is completed from dynamo α by current passing therefrom by wire 7 (see Fig. 2), distributing trolley α^1 , rail c , wire m , wire w to green lamp 10 in cabin 1 and from thence by wire t to rail l and then by way of the engine wheels and frame to the earth. A fourth circuit is at the same time completed from dynamo α by way of wire 7, distributing trolley α^1 , rail c , wire q^1 , wire u of signal cabin in the rear of cabin 1 (not shown as wiring and signals are same as in cabin 1) to lamp 12 in that cabin and earthed by wire t of that cabin and running rail l to the earth through the wheels and frame of the engine. The first-mentioned circuit indicates to the driver that his apparatus is in working order. The second shows the driver that his engine is on the signaling rails. The third shows the signalman in cabin 1 that the train is in his signaling area and the fourth indicates to the signalman in the cabin in the rear of cabin 1 that the train has cleared his section and entered the section under the control of cabin 1. When the train is on the ramp rails of cabin 1, as described, the driver by means of the switch g^5 may make contact with stud g^6 and thereby cause current to pass from dynamo α by wire 7, distributing trolley α^1 , ramp rail c , collecting trolley b , stud d^1 , left hand terminal f , wire g^1 , wire g^7 , switch g^5 , contact stud g^6 , wire g^2 , right hand terminal f , trolley b^1 , ramp rail c^1 , wire p to lamp 11, wire s^1 , wire t to running rail l and through wheels of engine to earth. By making and breaking this circuit by means of the switch g^5 the driver can give a code of signals by lamp 11 in cabin 1; when he does so he at the same time closes or completes another circuit from dynamo α , by wire 7, trolley α^1 , rail c , collecting trolley b , stud d^1 , left hand terminal f , wire g^1 , wire g^7 , switch g^5 , stud g^6 , wire g^2 , right hand terminal f , right hand stud d^1 , trolley b^1 , ramp rail c^1 ,

wire p , wire v^3 , wire v^4 , contact stud v^6 , lever handle r , stud v^5 , wire v^7 and wire g to ramp rail c of cabin 2 and by wires m and w in that cabin to green lamp 10 of cabin 2 ahead, the circuit being earthed by way of wire t of cabin 2 and the running rails l and then by the wheels and frame of the engine to the earth. The signalman of a signal cabin can reply to the driver of a train on the ramp rails of his section by means of his switch o by making and breaking contact between switch o and stud o^2 in his cabin. This completes a circuit as follows:—From dynamo α by wire 7, trolley α^1 to contact rail c , wire m , wire n , stud o^1 , switch o , stud o^2 , wire p , ramp rail c^1 , collecting trolley b^1 , stud d^1 , terminal f , wire g^2 to red lamp 2 in cab of engine and to earth by engine framework.

When the line ahead is not clear the signalman can block or stop a train entering his signaling area by placing the switch o into contact with the contact stud or piece o^2 and leaving it there until the obstruction is removed and the line cleared. When the switch o is on the contact piece o^2 a circuit is completed as follows from the dynamo α :—from dynamo α by wire 7, trolley α^1 , rail c , wire m , wire n , stud o^1 , switch o , stud o^2 , wire p , ramp rail c^1 , collecting trolley b^1 , stud d^1 , right terminal f , wire g^2 to red or danger lamp 2 in engine cab and to earth by way of engine framework. The lighting of lamp 2 indicates to the engine driver that the line ahead is blocked and that he must remain in the signaling area in which he receives the signal. At the same time current from the dynamo α passes by wire 7, trolley α^1 , rail c , wire m , wire n , stud o^1 , switch o , stud o^2 , wire p , wire s , to red lamp 11 in the signal cabin and then to earth by wire s^1 , wire t , rail l and framework of engine. This circuit confirms to the signalman that he has signaled to the train to stop. The signalman can also stop or block a train entering his section by pulling the signal lever r over so as to connect the stud contacts v^1 and v^2 . This completes a circuit from dynamo α as follows:—current from dynamo α passes by wire 7, trolley α^1 , rail c , wire m , wire v , stud v^1 , lever r , stud v^2 , wire v^3 , wire p , ramp rail c^1 , collecting trolley b^1 , stud d^1 , right terminal f , wire g^2 to red or danger lamp 2 in engine cab and to earth by way of engine framework. The lighting of lamp 2 indicates to the engine driver that the line ahead is blocked and that he must remain in the signaling area in which he receives the signal. At the same time current passes from dynamo α by wire 7, trolley α^1 , rail c , wire m , wire v , stud v^1 , lever r , stud v^2 , wire v^3 , wire p , wire s to red lamp 11 in the signal cabin and then to earth by wire s^1 , wire t , rail l and framework of engine. This circuit confirms to the signalman that he has signaled to the train to stop.

man that he has signaled to the train to stop.

If a train or engine is standing or moving on the part of the line under the control of cabin 2 and a train enters the signaling section controlled by cabin 1 and the signalman in cabin 1 either by mistake or otherwise gives the "clear" signal to the incoming train by pulling his lever r into contact 10 with the stud contacts v^5 and v^6 then, on the train entering his section, a circuit will be immediately completed whereby the red or danger lamp 2 in the engine cab will be lighted thereby warning the driver of the 15 fact that in spite of his signals he is not to proceed. This circuit which is from the dynamo α of the engine on the section controlled by cabin 2 is as follows:—from dynamo α by wire 7, trolley α^1 , rail c of cabin 20 2, connecting wire q , between cabin 2 and cabin 1, wire v^7 at cabin 1, contact stud v^5 , lever r , contact stud v^6 , wire v^4 , wire v^3 , wire p to rail c^1 , trolley b^1 of the engine at cabin 1 and from thence by right terminal f , wire 25 g^2 , to red lamp 2 and to earth by way of the engine framework. At the same time another circuit is completed from the dynamo α of the engine at cabin 2 through the danger lamp 11 in cabin 1 in the following 30 manner: from dynamo α by wire 7, trolley α^1 , ramp rail c , wire q from cabin 2 to cabin 1, wire v^7 , at cabin 1, contact stud v^5 , lever r , contact stud v^6 , wire v^4 , wire v^3 , wire p , wire s to red or danger lamp 11 then by wire s^1 35 and wire t to rail l and from thence by the wheels and frame of the engine to earth. This circuit indicates to the signalman of cabin 1 that he has made a mistake in giving the clear signal to the train entering his 40 section.

Having now fully described my invention what I claim and desire to secure by Letters Patent is:—

1. The combination, in an electrical signaling system such as described, of a ramp rail on the track, a source of electricity on the engine, a trolley on the engine in circuit with said source of electricity and adapted to engage said ramp rail, an electric lamp 45 on the engine, a second trolley adapted to engage the ramp rail, a contact on the engine in circuit with said lamp, a second contact on the engine connected with the source of electricity, a contact on the said second trolley 50 adapted to bridge said engine contacts, an electric lamp in the signal cabin, electrical connections from the said lamp in the signal cabin to the ramp rail, means in connection with the said second trolley whereby 55 the trolley ceases engaging the ramp rail its contact is caused to bridge the aforesaid engine contacts and connect the lamp on the engine with the source of electricity in order to light the same, a second electric 60 lamp on the engine and means whereby 65 lamp on the engine and means whereby

when the said second trolley engages the ramp rail the second lamp on the engine is connected with the second trolley whereby a connection is made from the source of electricity through the trolleys and ramp rail to the second lamp. 70

2. The combination, in an electrical signaling system such as described, of a ramp rail on the track, a source of electricity on the engine, a trolley on the engine in circuit with 75 said source of electricity and adapted to engage said ramp rail, an electric lamp on the engine, a second trolley adapted to engage the ramp rail, a contact on the engine in circuit with said lamp, a second contact on the engine connected with the source of electricity, a contact on the said second trolley adapted to bridge said engine contacts, an electric lamp in the signal cabin, electrical connections from the said lamp in the 80 signal cabin to the ramp rail, means in connection with the said second trolley whereby when the trolley ceases engaging the ramp rail its contact is caused to bridge the aforesaid engine contacts and connect the lamp on the engine with the source of electricity in order to light the same, a second electric lamp on the engine, a third contact on the engine in circuit with said second lamp on engine, and a second contact on the said second trolley adapted to contact with said third contact on the engine when the said 85 second trolley engages the ramp rail. 90

3. The combination, in an electrical signaling system such as described, of a ramp rail on the track, a source of electricity on the engine, a trolley on the engine in circuit with 100 said source of electricity and adapted to engage said ramp rail, an electric lamp on the engine, a second spring-depressed trolley adapted to engage the ramp rail, a contact on the engine in circuit with said lamp, a second contact on the engine connected with the source of electricity, a contact on the said second trolley adapted to bridge said engine contacts, when the trolley ceases engaging the ramp rail, to connect the lamp on the engine with the source of electricity in order to light the same, an electric lamp in the signal cabin, electrical connections from the said lamp in the signal cabin to the ramp rail, a second electric lamp on the engine and means whereby when the 110 said second trolley engages the ramp rail the second lamp on the engine is connected with the second trolley whereby a connection is made from the source of electricity through the trolleys and ramp rail to the second lamp. 115

4. The combination, in an electrical signaling system such as described, of a ramp rail on the track, a source of electricity on the engine, a trolley on the engine in circuit with 120 said source of electricity and adapted to engage said ramp rail, an electric lamp 125

on the engine, a second trolley adapted to engage the ramp rail, a terminal contact on the engine in circuit with said lamp, a second contact on the engine connected with the 5 source of electricity, a contact on the said second trolley adapted to bridge said engine contacts, an electric lamp in the signal cabin, electrical connections from the said lamp in the signal cabin to the ramp 10 rail, means in connection with the said second trolley whereby when the trolley ceases engaging the ramp rail its contact is caused to bridge the aforesaid engine contacts and connect the lamp on the engine with the 15 source of electricity in order to light the same, a second electric lamp on the engine, a third terminal contact on the engine in circuit with said second lamp on engine, and a second contact on the said second trolley 20 adapted to contact with said third terminal contact on engine when the second trolley engages the ramp rail.

5. The combination, in an electrical signaling system such as described, of a ramp rail on the track, a source of electricity on 25 the engine, a trolley on the engine in circuit with said source of electricity and adapted to engage said ramp rail, an electric lamp on the engine, a second trolley adapted to 30 engage the ramp rail, a terminal on the engine in circuit with said lamp, an insulated contact in circuit with the source of electricity on the engine, a contact on the said second trolley adapted to bridge said terminal and contact, an electrical lamp in the 35 signal cabin, electrical connections from the said lamp in the signal cabin to the ramp rail, and means causing the contact on said second trolley to contact with the engine 40 terminal and contact so long as said second trolley is off the ramp rail thereby maintaining an electrical connection between the source of electricity and the lamp on the engine and keeping said lamp lighted.

45. 6. The combination, in an electrical signaling system such as described, of a ramp rail on the track, a source of electricity on the engine, a trolley on the engine in circuit with said source of electricity and adapted 50 to engage said ramp rail, an electric lamp on the engine, a second trolley adapted to engage the ramp rail, a terminal on the engine in circuit with said lamp, a contact in circuit with the source of electricity on the 55 engine, a contact on the said second trolley adapted to bridge said terminal and contact, an electrical lamp in the signal cabin, electrical connections from the said lamp in the signal cabin to the ramp rail, means 60 causing the contact on said second trolley to bridge the engine terminal and contact so long as said second trolley is off the ramp rail thereby maintaining an electrical connection between the source of electricity and

the lamp on the engine thus keeping said 65 lamp lighted, a second electric lamp on the engine, a second contact on the engine in circuit with said second lamp and a second contact on the second trolley adapted to contact with said second contact on the engine 70 and thus connect the source of electricity through the trolleys and ramp rail, with the second lamp when the said second trolley engages said ramp rail.

7. The combination, in an electrical signaling system such as described, of a ramp rail on the track, a source of electricity on the engine, a trolley on the engine in circuit with said source of electricity and adapted to engage said ramp rail, an electric lamp 80 on the engine, a second trolley adapted to engage the ramp rail, a terminal on the engine in circuit with said lamp, an insulated contact in circuit with the source of electricity, a contact on the said second trolley 85 adapted to bridge said terminal and the insulated contact and means for maintaining the contact of the second trolley in electrical contact with the said terminal and contact when the second trolley is out of engagement with the ramp rail.

8. The combination, in an electrical signaling system such as described, of a ramp rail on the track, a source of electricity on the engine, a trolley on the engine in circuit 95 with said source of electricity and adapted to engage said ramp rail, an electric lamp on the engine, a second trolley adapted to engage the ramp rail, a terminal on the engine in circuit with said lamp, an insulated 100 contact in circuit with the source of electricity, a second lamp on the engine, a second terminal on the engine in circuit with said second lamp, and two contacts on the second trolley the one contact adapted to 105 bridge the first terminal on the engine and the insulated contact when the second trolley is off the ramp rail and the other contact adapted to connect the ramp rail and the second terminal on the engine when the 110 second trolley is on the ramp rail.

9. The combination, in an electrical signaling system such as described, of a ramp rail on the track, a source of electricity on the engine, a trolley on the engine in circuit 115 with said source of electricity and adapted to engage said ramp rail, an electric lamp on the engine, a second trolley adapted to engage the ramp rail, a long terminal on the engine in circuit with said lamp, an insulated contact in circuit with the source of electricity, a second lamp on the engine, a second short terminal on the engine in circuit with said second lamp, and two contacts on the second trolley the one contact 120 adapted to bridge the long terminal on the engine and the insulated contact when the second trolley is off the ramp rail and the 125

other contact adapted to connect the ramp rail with the short terminal on the engine when the second trolley is on the ramp rail.

10. The combination, in an electrical signaling system such as described, of two ramp rails on the track, means whereby the two ramp rails may be electrically connected, a source of electricity on the engine, a trolley on the engine in circuit with said source of electricity and adapted to engage one of the said ramp rails, an electric lamp on the engine, a second trolley adapted to engage the same ramp rail, a contact on the engine in circuit with said lamp, a second contact on the engine connected with the source of electricity, a contact on the second trolley adapted to bridge said engine contacts, a second electric lamp on the engine, a third contact on the engine in circuit with the second electric lamp, a contact on the second trolley adapted to contact with the third contact on the engine, a third electric lamp on the engine, a fourth contact on the engine in circuit with said third lamp, a third trolley on the engine adapted to engage a different ramp rail from the other trolleys and a contact on the third trolley adapted to contact with the fourth contact on the engine.

11. The combination, in an electrical signaling system such as described, of two ramp rails on the track, means whereby the two ramp rails may be electrically connected, a source of electricity on the engine, a trolley on the engine in circuit with said source of electricity and adapted to engage one of the said ramp rails, an electric signaling device on the engine, a second trolley adapted to engage the same ramp rail, a contact on the engine in circuit with said electric signaling device, a second contact on the engine connected with the source of electricity, a contact on the second trolley adapted to bridge said engine contacts, a second electric signaling device on the engine, a third contact on the engine in circuit with the second electric signaling device, a contact on the second trolley adapted to contact with the third contact on the engine, a third electric signaling device on the engine, a fourth contact on the engine in circuit with said third signaling device, a third trolley on the engine adapted to engage a different ramp rail from the other trolleys and a contact on the third trolley adapted to contact with the fourth contact on the engine.

12. The combination, in an electrical signaling system such as described, of two ramp rails on the track, means whereby the two ramp rails may be electrically connected, a source of electricity on the engine, a trolley on the engine in circuit with said source of electricity and adapted to engage one of the said ramp rails, an electric lamp on the engine, a second trolley adapted to engage the same ramp rail, a contact on the engine in

circuit with said lamp, a second contact on the engine connected with the source of electricity, a contact on the second trolley adapted to bridge said engine contacts, an electric lamp in the signal cabin, electric connections from the said lamp in the signal cabin to a ramp rail, a second electric lamp on the engine, a third contact on the engine in circuit with the second electric lamp, a contact on the second trolley adapted to contact with the third contact on the engine, a third electric lamp on the engine, a fourth contact on the engine in circuit with said third lamp, a third trolley on the engine adapted to engage a different ramp rail from the other trolleys and a contact on the third trolley adapted to contact with the fourth contact on the engine.

13. The combination, in an electrical signaling system such as described, of two ramp rails on the track, means whereby the two ramp rails may be electrically connected, a source of electricity on the engine, a trolley on the engine in circuit with said source of electricity and adapted to engage one of the said ramp rails, an electric lamp on the engine, a second trolley adapted to engage the same ramp rail, a contact on the engine in circuit with said lamp, a second contact on the engine connected with the source of electricity, a contact on the second trolley adapted to bridge said engine contacts, an electric lamp in the signal cabin, electric connections from the said lamp in the signal cabin to the same ramp rail, a second electric lamp in the signal cabin, electric connections from said second lamp in the cabin to the second ramp rail, a second electric lamp on the engine, a third contact on the engine in circuit with the second electric lamp, a contact on the second trolley adapted to contact with the third contact on the engine, a third electric lamp on the engine, a fourth contact on the engine in circuit with said third lamp, means whereby said third and fourth contacts on the engine may be connected and disconnected, a third trolley on the engine adapted to engage the second ramp rail and a contact on the third trolley adapted to contact with the fourth contact on the engine.

14. The combination, in an electrical signaling system such as described, of two ramp rails on the track, means whereby the two ramp rails may be electrically connected, a source of electricity on the engine, a trolley on the engine in circuit with said source of electricity and adapted to engage one of the said ramp rails, an electric lamp on the engine, a second trolley adapted to engage the same ramp rail, a contact on the engine in circuit with said lamp, a second contact on the engine connected with the source of electricity, a contact on the second trolley adapted to bridge said engine

contacts, an electric lamp in the signal cabin, electric connections from the said lamp in the signal cabin to the same ramp rail, a second electrical lamp in the signal cabin, 5 electric connections from said second lamp in the cabin to the second ramp rail, a third electric lamp in the signal cabin, means whereby said third lamp in the cabin may be electrically connected with the second ramp rail, a second electric lamp on the engine, a third contact on the engine in circuit with the second electric lamp, a contact on the second trolley adapted to contact with the third contact on the 10 engine, a third electric lamp on the engine, a fourth contact on the engine in circuit with said third lamp, means whereby said third and fourth contacts on the engine may be connected and disconnected, a third 15 trolley on the engine adapted to engage the second ramp rail and a contact on the third trolley adapted to contact with the fourth contact on the engine.

15. The combination, in an electrical signaling system such as described, of two ramp rails on the track, means whereby the two ramp rails may be electrically connected, a source of electricity on the engine, a trolley on the engine in circuit with said 20 source of electricity and adapted to engage one of the said ramp rails, an electric lamp on the engine, a second trolley adapted to engage the same ramp rail, a contact on the engine in circuit with said lamp, a second 25 contact on the engine connected with the source of electricity, a contact on the second trolley adapted to bridge said engine contacts, an electric lamp in the signal cabin, electric connections from the said lamp in the signal cabin to the same ramp rail, a second electric lamp in the signal cabin, electric connections from said second lamp in the cabin to the second ramp rail, a third 30 electric lamp in the signal cabin, means whereby said third lamp in the cabin may be electrically connected with the second ramp rail, a ramp rail in the next signaling area ahead, electric connections from said third lamp in the cabin to said ramp rail of the next signaling area ahead, a second 35 electric lamp on the engine, a third contact on the engine in circuit with the second electric lamp, a contact on the second trolley adapted to contact with the third contact on the engine, a third electric lamp on the engine, a fourth contact on the engine in circuit with said third lamp, means whereby said third and fourth contacts on the engine may be connected and disconnected, a third 40 trolley on the engine adapted to engage said second ramp rail and a contact on the third trolley adapted to contact with the fourth contact on the engine.

45 whereby said third lamp in the cabin may be electrically connected with the second ramp rail, a ramp rail in the next signaling area ahead, electrical connections from the said third lamp in the cabin to said ramp rail of the next signaling area ahead, a second 50 electric lamp on the engine, a third contact on the engine in circuit with the second electric lamp, a contact on the second trolley adapted to contact with the third contact on the engine, a third electric lamp on the engine, a fourth contact on the engine in circuit with said third lamp, means whereby said third and fourth contacts on the engine may be connected and disconnected, a third 55 trolley on the engine adapted to engage the second ramp rail and a contact on the third trolley adapted to contact with the fourth contact on the engine.

60 whereby said third lamp in the cabin may be electrically connected with the second ramp rail, a ramp rail in the next signaling area ahead, electrical connections from the said third lamp in the cabin to said ramp rail of the next signaling area ahead, a second electric lamp on the engine, a third contact on the engine in circuit with the second electric lamp, a contact on the second trolley adapted to contact with the third contact on the engine, a third electric lamp on the engine, a fourth contact on the engine in circuit with said third lamp, means whereby said third and fourth contacts on the engine may be connected and disconnected, a third trolley on the engine adapted to engage the second ramp rail and a contact on the third trolley adapted to contact with the fourth contact on the engine.

65 16. The combination, in an electrical sig-

naling system such as described, of two ramp rails on the track, means whereby the two ramp rails may be electrically connected, a source of electricity on the engine, a trolley on the engine in circuit with said source of electricity and adapted to engage one of the said ramp rails, an electric lamp on the engine, a second trolley adapted to engage the same ramp rail, a contact on the engine in circuit with said lamp, a second contact on the engine connected with the source of electricity, a contact on the second trolley adapted to bridge said engine contacts, an electric lamp in the signal cabin, electric connections from the said lamp in the signal cabin to the same ramp rail, a second electric lamp in the signal cabin, electric connections from said second lamp in the cabin to the second ramp rail, a third electric lamp in the signal cabin, means whereby said third lamp in the cabin may be electrically connected with the second ramp rail, a ramp rail in the next signaling area ahead, electric connections from said third lamp in the cabin to said ramp rail of the next signaling area ahead, a second electric lamp on the engine, a third contact on the engine in circuit with the second electric lamp, a contact on the second trolley adapted to contact with the third contact on the engine, a third electric lamp on the engine, a fourth contact on the engine in circuit with said third lamp, means whereby said third and fourth contacts on the engine may be connected and disconnected, a third trolley on the engine adapted to engage said second ramp rail and a contact on the third trolley adapted to contact with the fourth contact on the engine.

17. The combination, in an electrical signaling system such as described, of a ramp rail on the track, a source of electricity on the engine, a trolley on the engine in circuit with said source of electricity and adapted to engage said ramp rail, an electric signaling device on the engine, a second trolley adapted to engage the ramp rail, a contact on the engine in circuit with said electric signaling device, a second contact on the engine connected with the source of electricity, a contact on the said second trolley adapted to bridge said engine contacts, an electric signaling device in the signal cabin, electrical connections from the said electric signaling device in the signal cabin to the ramp rail, means in connection with the said second trolley whereby when the trolley ceases engaging the ramp rail its contact is caused to bridge the aforesaid engine contacts and connect the electric signaling device on the engine with the source of electricity and coöperate the same, a second electric signaling device on the engine and means whereby when the said second trolley engages the ramp rail the second elec-

tric signaling device on the engine is operated.

18. The combination, in an electrical signaling system such as described, of a ramp rail on the track, a source of electricity on the engine, a trolley on the engine in circuit with said source of electricity and adapted to engage said ramp rail, an electric signaling device on the engine, a second trolley adapted to engage the ramp rail, a contact on the engine in circuit with said electric signaling device, a second contact on the engine connected with the source of electricity, a contact on the said second trolley adapted to bridge said engine contacts, an electric signaling device in the signal cabin, electrical connections from the said signaling device in the signal cabin to the ramp rail, means in connection with the said second trolley whereby when the trolley ceases engaging the ramp rail its contact is caused to bridge the aforesaid engine contacts and connect the electric signaling device on the engine with the source of electricity and so operate the same, a second electric signaling device on the engine, a third contact on the engine in circuit with said second electric signaling device on the engine, and a second contact on the said second trolley adapted to contact with said third contact on the engine when the second trolley engages the ramp rail.

19. The combination, in an electrical signaling system such as described, of two ramp rails on the track, a source of electricity on the engine, a trolley on the engine in circuit with said source of electricity and adapted to engage one of the said ramp rails, an electric signaling device on the engine, a second trolley adapted to engage the same ramp rail, a contact on the engine in circuit with said signaling device, a second contact on the engine connected with the source of electricity, a contact on the second trolley adapted to bridge said engine contact, an electric signaling device in the signal cabin, electric connections from the said signaling device in the signal cabin to the same ramp rail, a second electric signaling device in the signal cabin, electric connections from said second signaling device in the cabin to the second ramp rail, a third electric signaling device in the signal cabin, a third ramp rail in the next section of the track ahead, a signaling device in the next cabin ahead, electric connections from said third ramp rail to the signaling device of the next cabin ahead, means whereby the second ramp rail may be electrically connected with the third ramp rail, and a signaling device in the next cabin in rear, an electric connection from the first ramp rail to said signaling device in next cabin in rear, a second electric signaling device on

the engine, a third contact on the engine in circuit with the second electric signaling device, a contact on the second trolley adapted to contact with the third contact on the engine, a third electric signaling device on the engine, a fourth contact on the engine in circuit with said third signaling device, means whereby said third and fourth contacts on the engine may be connected and disconnected, a third trolley on the engine adapted to engage the second ramp rail and a contact on the third trolley adapted to contact with the fourth contact on the engine and means whereby the first ramp rail can be electrically connected with the second ramp rail through the signal cabin.

20. The combination, in an electrical signaling system such as described, of a ramp rail on the track, a source of electricity on the engine, a trolley on the engine in circuit with said source of electricity and adapted to engage said ramp rail, an electric lamp on the engine, a second trolley adapted to engage the ramp rail, a contact on the engine in circuit with said lamp, a second contact on the engine connected with the source of electricity, a contact on the said second trolley adapted to bridge said engine contacts, an electric lamp in the signal cabin, electrical connections from the said lamp in the signal cabin to the ramp rail, means in connection with the said second trolley whereby when the trolley ceases engaging the ramp rail its contact is caused to bridge the aforesaid engine contacts and connect the lamp on the engine with the source of electricity and so light the same, a second electric lamp on the engine, means whereby when the said trolley engages the ramp rail the second lamp on the engine is lighted, a third lamp on the engine, a second lamp in the signal cabin and means whereby the third lamp on the engine and the second lamp in the cabin can be flashed in and out.

21. The combination, in an electrical signaling system such as described, of a ramp rail on the track, a source of electricity on the engine, a trolley on the engine in circuit with said source of electricity and adapted to engage said ramp rail, an electric lamp on the engine, a second trolley adapted to engage the ramp rail, a contact on the engine in circuit with said lamp, a second contact on the engine connected with the source of electricity, a contact on the said second trolley adapted to bridge said engine contacts an electric lamp in the signal cabin, electrical connections from the said lamp in the signal cabin to the ramp rail, means in connection with the said second trolley whereby when the trolley ceases engaging the ramp rail its contact is caused to bridge the aforesaid engine contacts and

close the circuit through the lamp on the engine and light the same, a second electric lamp on the engine, means whereby when the said trolley engages the ramp rail the 5 second lamp on the engine is lighted, a third lamp on the engine a second lamp in the signal cabin, a lamp in the next cabin ahead and means whereby the third lamp on the engine, the second lamp in the cabin and

the lamp in the cabin ahead can be flashed 10 in and out.

In testimony whereof I affix my signature in presence of two witnesses.

GEORGE HERBERT BROWN.
